UNITED STATES PATENT OFFICE.

FREDERICK G. CRABB, OF NEW HAVEN, CONNECTICUT.

DESIGN FOR A THIMBLE.

SPECIFICATION forming part of **Design No. 22,000**, dated November 22, 1892.

Application filed October 31, 1892. Serial No. 450,561. Term of patent 7 years.

To all whom it may concern:

Be it known that I, FREDERICK G. CRABB, of New Haven, in the county of New Haven and State of Connecticut, have invented a new 5 Design for a Thimble; and I do hereby declare the following, when taken in connection with accompanying drawing and the letters of reference marked thereon, to be a full, clear, and exact description of the same, and which 10 said drawing constitutes part of this specification, and represents a view in side elevation of a thimble containing my design.

This invention relates to a design for a thimble; and it consists in the configuration 15 and ornamentation as shown in the accompanying illustration.

The main portion A of my newly-designed thimble has the configuration and appearance of a nutmeg slightly enlarged and cut off at 20 one end where it merges into a slightly-taper-

ing band B, from the inner edge of which springs a fillet of leaves C, interspersed with buds like the bud D. The band, which is otherwise plain, has the appearance of being ornamented with a tendril E, one end whereof 25 has a cup-like termination containing a bud G, larger than the bud D, while the convolutions of the other end of the tendril form the letters "Conn."

I claim—

The design for a thimble, as herein shown and described.

In testimony whereof I have signed this specification in the presence of two subscribing witnesses.

FREDK. G. CRABB.

Witnesses:

GEO. D. SEYMOUR,
LILLIAN D. KELSEY.
